(57)

CLAIM

The ornamental design for a syringe barrel, as shown and described.

DESCRIPTION

FIG. 1 is a front and bottom perspective view of a syringe barrel in accordance with our new design;

FIG. 2 is a left side elevational view thereof;

FIG. 3 is a right side elevational view thereof;

FIG. 4 is a top plan view thereof;

FIG. 5 is a bottom plan view thereof;

FIG. 6 is a front elevational view thereof; and,

FIG. 7 is a rear elevational view thereof.

The features shown in broken lines depict environmental structure only and form no part of the claimed design.
